UNITED STATES PATENT OFFICE.

JOHN M. CALDWELL, OF SOUTHMAYDE, TEXAS.

COTTON CHOPPER.

Application filed September 8, 1924. Serial No. 736,601.

This invention relates to an improved cotton chopper which I have designed to supersede similar marketed and patented devices, with which I am familiar.

5 The improved chopper is constructed principally from a plurality of angle irons which are so related as to provide runners, plow beam mounting means, etc., suitable braces being provided to secure rigidity of structure, and the parts being so arranged as to make for ready adjustment.

Other features and advantages may become apparent from the following description and drawings.

10 In the accompanying drawing, forming a part of this application, and in which like numerals are employed to designate like parts throughout the same:—

Figure 1 is a top plan view of a cotton chopper constructed in accordance with the present invention.

Figure 2 is a rear elevational view thereof.

Figure 3 is a side elevation, and

25 Figure 4 is an enlarged detail view showing the method of adjustment.

In carrying out the invention, a suitably designed supporting frame is provided. The frame comprises horizontal angle irons 1 at its bottom, which functions as runners. The forward ends of the runners may be directed upwardly as indicated at 2, to facilitate travel of the device over the surface to be traversed. Connected to and extending upwardly from the runners are pairs of spaced irons 3, which are connected at their upper ends to the upper side bars 4. The side bars may be connected together by front and rear cross bars 5 and 6 respectively. If desired, intermediate cross bars may be provided for increasing the strength of the device. At this time, I wish to direct attention to the fact that the cross bars 5 and 6 are composed of sections 7, which have their inner ends overlapped and provided with aligned apertures for passage of retaining bolts 8. Obviously, this arrangement permits the sections to be adjusted on each other to increase or decrease the width of the machine. As better seen, in Figure 3, a pair

50 of horizontal arms 9 are provided, these being pivotally and adjustably connected at their forward ends as at 10, with the front vertical bars and being adjustably connected at their opposite ends in the manner shown 55 with the rear vertical bars. These arms serve to support a plurality of plow stand-

ards 11 and 12, which are provided at their lower ends with pivotally mounted plow heads 13. If desired, suitable spring means 14 may be provided between the standards 60 and plow heads to maintain the latter in yieldable engagement with the surface. In this manner, breakage of the plow points and heads is overcome to a noticeable extent. In practice, any number of plows may be used. 65 For instance, the plows may be arranged in front and rear transverse rows as better seen in Figure 3, or a single row may be utilized. The plows of the rear row may be directly connected with the arms 9, directly in back 70 of the runners. This row may include two or three plows. The front row preferably comprises a number of plows which are supported from a board or the like 15, which is in turn supported from the arms 9. The 75 plows are removable, and in practice, different sizes of plow heads will be used, according to the spaces existing.

For the purpose of swinging the arms 9 upon their pivots to adjust the depth of 80 cut of the plow, suitable hoisting means is provided. In the present instance, the hoisting means comprises a pair of pivotally mounted levers 16. The levers are provided at their lower ends with chains or 85 suitable flexible connections 17, which are, in turn, connected with the intermediate portions of the arms 9. Exerting a rearward pull upon the levers will lift the arms to the desired angular position. In practice, 90 segmental racks 17 will be secured to the side bars 4 and the levers will be provided with latches for cooperation with the teeth of the rack. Thus, the arms 9 will be held 95 in any position to which they are adjusted.

Referring again to Figure 3, it will be seen that the forward ends of the side bar 4 are directed downwardly, as indicated at 19 and the free ends co-act with the corresponding ends of the upturned portions 100 of the runners to provide adjusting means for the draft connection 20. This point has suitably directed braces thereon to obviate torsional strains.

In practice, the plow carrying arm will 105 be swung to the desired angular position with respect to the surface of the ground to be traversed, thus positioning the plows at a point to obtain the desired depth of cut. The range of adjustment is considerable, inasmuch as the pivotal connections of the arms are adjustable as are the rear 110

ends thereof. The hoisting means provided is such as to permit ready adjustment and to maintain the parts in a set position. The device is now dragged crosswise of the field and the desired plants are severed. Utilization of a machine of this class will undoubtedly reduce the labor now necessary and will decidedly aid the cotton chopping operation.

10 While I have shown and described the preferred embodiment of the invention, it is to be understood that minor changes coming within the field of invention as claimed may be resorted to, if desired.

15 I claim:—

In a structure of the class described, a pair of spaced end frames disposed in parallelism, each frame being composed of angle bars, there being top and bottom hori-

zontal bars and forward and rearward vertical bars, the forward ends of the horizontal bars being directed toward each other in converging relation and secured together to provide draft connecting means, the upturned end of the lower bar converting the latter into a runner, and angular cross-members connecting said frames together in assembled relation, said cross members being composed of sections adjustably connected with each other, and a pair of horizontal plow carrying arms, there being an arm for each end frame, said arm being adjustably connected with the vertical bars of the respective frame and being provided with depending standards.

35 In testimony whereof I affix my signature.

JOHN M. CALDWELL.
